C. C. SMALLING,
RAIL ANCHOR AND BRACE,
APPLICATION FILED APR. 5, 1915.

1,186,448.

Patented June 6, 1916.

UNITED STATES PATENT OFFICE.

CLARENCE C. SMALLING, OF WINCHESTER, KENTUCKY.

RAIL ANCHOR AND BRACE.

1,186,448.

Specification of Letters Patent.

Patented June 6, 1916.

Application filed April 5, 1915. Serial No. 19,327.

To all whom it may concern:

Be it known that I, CLARENCE C. SMALLING, a citizen of the United States, residing at Winchester, in the county of Clark, State of Kentucky, have invented certain new and useful Improvements in Rail Anchors and Braces; and I do hereby declare the following to be a full, clear, and exact description of the invention, such as will enable others skilled in the art to which it appertains to make and use the same.

This invention relates to a rail anchor and brace.

An object of the invention resides in the provision of a device of this character by means of which a rail may be securely held upon a tie and prevented from either longitudinal or lateral movement.

A further object of the invention resides in so constructing the device that rails of various thicknesses may be held upon the tie.

With these and other objects in view, such as will appear as the description progresses, my invention comprises the combination and arrangement of parts as set forth in and falling within the scope of the appended claims.

Referring to the drawing: Figure 1 is a side elevation of a tie with the rails clamped thereon by means of devices constructed in accordance with my invention. Fig. 2 is a plan view. Fig. 3 is a longitudinal sectional view. Fig. 4 is a section on line 4-4 of Fig. 3 taken in a vertical plane through one of the braces on the end of the tie on which the abutting ends of two rails are secured. Fig. 5 is a horizontal sectional view, showing the manner in which the wedge blocks 10 coöperate with the brace members. Fig. 6 is a detail sectional view, showing the manner in which the clamps for the rail on the other end of the tie are mounted in the tie.

Referring to the drawing wherein like parts are indicated by like characters throughout the several views: In the drawings, I have shown my device attached to a tie such as disclosed in my application #16,147 filed March 22, 1915, but it is to be understood that the device can be used on ties of various other formations, which ties must, however, be of trough construction having side flanges. The tie illustrated is of trough formation having a bottom 1, side flanges 2 and transversely extending walls 3, 4, 5 and 6, which divide the tie into com-

partments 7, 8, 9, 10 and 11, respectively. The compartments 8 and 10 have cushion blocks 12 therein on which the rails are supported and suitably secured. The construction of this tie is, as heretofore stated, as described in the above mentioned application.

I will now describe the form of my device for holding the two abutting ends of adjacent rails upon one end of the tie. This form is illustrated on the left end of the tie shown in Fig. 1 of the drawing. I have provided a clamping member 13 having an arched portion 14 in the inner edge of which is formed a groove 15, the said groove having an inclined inner face 16, as shown in Fig. 5 of the drawing. This member is provided with spaced legs 17 having alined apertures 18 therein and outwardly extending shoulders 19 which are formed at the junctures between the legs and the arched portion 14. When this clamping member is in position on the tie the legs 17 rest upon the bottom of the tie within the chamber 7 and the shoulders 19 bear upon the upper edges of the side flanges 2. The clamping member 13 is secured in this position by a bolt 20 which passes through the apertures 18 in the legs 17 and through the flanges 2. 80

At this time the inner edge of the clamping member 13 is in slightly spaced relation to the abutting ends of the rail and is located between the base and the tread of the rail so that it overhangs the base. A second 90 clamping member 21 having an arched portion 22 is provided. This clamping member, when in use, is located to the other side of the rail and in the chamber 9. It is provided with a groove 23 in its inner edge, the inner 95 face 24 of which is inclined, but in the opposite direction to that in which the face 16 of the groove 15 is inclined. Legs 25 are provided on the lower end of the arched portion 22 and have alined apertures 26 therein. At 100 the junctures, between these legs and the arched portion 22, shoulders 27 are formed. When in use the clamping member 21 is secured within the chamber 9 by a bolt 28 which passes through the apertures 26 in 105 the legs 25 and through the side flanges 2. This secures the clamping member 21 in such position that the legs rest upon the bottom of the tie, the shoulders 27 bear upon the upper edges of the flanges 2 and the inner edge of the arched portion 22 is in slight 110 spaced relation to the web of the rail.

In order that the abutting ends of the rails may be secured between these clamping members 18 and 21, I have provided a wedge block 29 of angular form having a horizontal portion and a vertical portion. The vertical portion is adapted to bear against the webs of the meeting ends of the rails. The horizontal portion of the block 29 is provided with an inclined edge 30 which is adapted to ride upon the inclined face 24 of the groove 23. This horizontal portion is further provided, adjacent its small end, with a plurality of longitudinally arranged holes 31 in which a pin 32 is adapted to be mounted so as to contact with the adjacent side of the clamping member 21. I have further provided a wedge block 33 having a vertical portion 34 and a horizontal portion 35 which extends outwardly from the vertical portion along a central line and the outer edge of which is inclined. This vertical portion is adapted to bear against the webs of the adjacent ends of the rails and to bridge the joint, while the horizontal portion is adapted to ride within the groove 15 in the clamping member 18 so that its inclined edge rides upon the inclined face of the groove 15. This horizontal portion is further provided with a plurality of apertures 36 through which a pin 37 is adapted to extend and contact with the adjacent face of the clamping member 18.

In use after the clamping members 18 and 21 have been secured in place the wedge blocks 29 and 33 are inserted between the clamping members and the webs of the rails in the manner described and are pushed inwardly until the rails are tightly clamped, at which time the pins 32 and 37 are inserted through the respective holes or apertures 31 and 36 so that the wedge blocks will be prevented from accidental displacement. The assembly of the device in this manner will prevent the rails from creeping apart or from relative lateral movement as will be readily appreciated.

Now in the form of my device designed for application to the other end of the tie, where a single rail passes thereover, I have

provided a clamp 38 which has a portion 39 adapted to overlie and bear upon the base of the rail and a second overhanging portion 40 which is adapted to bear upon the upper edge of one of the flanges 2. This clamp 38 is provided with a downwardly extending leg 41 which rests upon the bottom of the tie within the chamber 11 and against the inner faces of the wall 6 and the adjacent flange 2. In order that this clamp 38 may be secured in this position, I have provided the same with an aperture, through which a bolt 43 is adapted to extend and be secured to the flange 2 by suitable threads. A similar clamping member 44 is provided which is located in the chamber 9 so as to engage the inner side of the base of the rail.

While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the invention or without exceeding the scope of the appended claim.

What I claim is:—

The combination with a trough-shaped tie having side flanges and spaced transversely extending walls, of clamping members detachably mounted on said tie, the said clamping members including arched portions adapted to overhang the base of a rail and legs arranged to rest upon the bottom of the tie, the said clamping members being further provided with shoulders bearing upon the upper edges of the said flanges and wedge blocks adjustably mounted on the inner edges of said clamping members and adapted to secure a rail between the same.

In testimony whereof, I affix my signature, in the presence of two witnesses.

CLARENCE C. SMALLING.

Witnesses:

W. P. HARRISON,
S. W. POWELL.
